UNITED STATES PATENT OFFICE

SIDNEY B. MERRILL, OF CINCINNATI, OHIO, ASSIGNOR TO THE E. W. VANDUZEN COMPANY, OF CINCINNATI, OHIO, A CORPORATION OF OHIO

STRIKING MECHANISMS FOR BELLS

Application filed March 18, 1931. Serial No. 523,599.

In bells for ordinary purposes, which are caused to ring by a semi-rotation about an axis, and which have an interiorly pivoted clapper or striking mechanism, it has long been realized that some means for controlling the action of the clapper is highly desirable. The best performance is secured from the bell when the clapper strikes it a sharp, clean blow, and then is immediately removed from contact with the bell itself, so that the clapper neither dampens the sound of the bell by lying against the strike or thickened portion thereof, nor produces a disagreeable noise by vibrating against the bell surface. It is also highly desirable to avoid a second or after blow of the clapper against the bell surface. These considerations become of particular importance, since it is generally not practicable to control with exactness the arc through which the bell swings.

Hitherto, it has been proposed to control the striking of the clapper by means of a pair of leaf springs, one lying on either side of the clapper, directly in its path of movement in striking the bell. This method of control has been relatively successful, but it has certain inherent defects which it is the primary object of my present invention to overcome. In the said structure when the clapper contacts with the leaf spring initially, a good deal of the energy is absorbed. The back pressure of the leaf spring, of course, increases as it flexes; but the spring must be very carefully adjusted to the weight of the clapper if advantageous results are to be secured. If the spring is too light it may not immediately remove the clapper from the surface of the strike, and not infrequently it permits an after blow. If the spring is too strong, the energy of the stroke is largely dissipated, and the full, clear volume of the bell is not realized. The balancing of the several features is an extremely delicate operation, and it has in general been found necessary with such controlling mechanisms to employ a fairly stiff

spring and a very heavy clapper. An object of my invention, therefore, is to provide means for controlling the ringing of a bell whereby the necessary weight of the clapper may be cut down.

In connection with these features of necessary adjustment, it may also be pointed out that the flexing of the leaf spring is necessarily quite severe, for which reason it is likely to be progressively distorted by the continued ringing of the bell, so that the predetermined adjustments tend to become destroyed. Still another object of my invention, therefore, is the provision of means for controlling the action of the clapper in a bell, which means are not liable to come out of adjustment, but which are easily proportioned to exert a controlled pressure upon the clapper.

These and other objects of my invention which will be set forth hereinafter or will be apparent to one skilled in the art upon reading these specifications, I accomplish by that certain construction and arrangement of parts of which I shall now describe a preferred embodiment, reference being had to the drawings, in which:

Figure 1 is a sectional view of the bell showing a side elevation of my controlling mechanism.

Fig. 2 is a fragmentary view showing my controlling mechanism in end elevation.

In Fig. 1 I have indicated a bell at 1, having any adequate top plate or portion 2 adapted to be fastened to or to be grasped by suspended means, including the regular yoke. The member 2 has a flange plate 2a adapted to contact the top of the bell, and beneath this, located essentially within the bell, there is a member 3, having a flange plate 3a, engaging beneath the top of the bell. The members 2 and 3 are held together by bolts and nuts 5.

The construction hereinabove just described is common to bells as commercially manufac-

tured, but is not a limitation upon my invention, my invention being applicable to bells otherwise constructed. A clapper 6, having an enlarged striking portion 7, is fitted with a bearing member 8, by which it may be pivoted upon a pin 9, which passes through ears 10, usually a part of the member 3. The motion of the clapper about its pivot is thus restricted to a plane transverse to the pin 9, and the bell is so hung upon its yoke as to produce motion in this plane when the bell is rocked back and forth. Rigidly attached to the top of the bell, as by being riveted, welded, or otherwise fastened to the ear 10, upon the member 3, I provide an arm 11, which extends downwardly along side of and usually in substantial parallelism with the shank of the clapper 6 when the bell is hanging straight downwardly. This arm is of less length than the clapper, and it may be provided at its lower end with a perforation or eye 12, to which a spring controlling mechanism, hereinafter to be described, may be attached. I also provide my clapper with an eye 13, preferably cast integrally therewith, to which the other end of the spring mechanism may be attached.

My spring controller comprises a coiled spring 14, having means 15 by which it may be attached either directly to the eyes 12 and 13, or to these eyes by means of suitable intervening members 16, such as chain links. The lower links 16' are round links, to permit play without the possibility of kinking.

In this way I have provided a very simple controlling device, which has proved entirely adequate in operation. The spring 14 will, of course, be proportioned in the force necessary to stretch it to the weight of the clapper 6, and it is not difficult to select for an individual clapper a coil spring of such strength as will adequately control its movement. A wide variety of springs and clappers may be employed, and in general I have been able, in accordance with my invention, to produce a clearer and more perfect ringing of a given bell with a lighter clapper than it has been possible to use heretofore. When the clapper is at rest, as shown in full lines in Fig. 1, I prefer to leave my spring 14 slack. The clapper is thus free at the commencement of the stroke, and the pull on the clapper is substantially transverse to its movement at the end of the stroke. The back force is thus applied somewhat before the clapper swings into striking position and is at a maximum when the clapper lies in the positions shown in the dotted lines in Fig. 1, but the force applied is regular and powerful, and the spring member itself has substantially no momentum which need be considered in controlling the action of the clapper. Thus my device, while it permits a clear, sharp blow, nevertheless entirely prevents either a resting of the clapper against the bell surface, and

vibration of the clapper in connection with the surface, or an after stroke; nor is it possible for my device to get out of adjustment, since the resistance applied is not dependent upon the configuration of members which are caused to follow the clapper and are bent into new configurations by its movement. My spring 14 retains a constant potential force, and so long as this remains constant the control of the clapper is very accurate, quite irrespective of the arc through which the bell is swung.

My device compensates for wear upon the surface of the clapper and the bell. It is simple and cheap in construction, and easily replaced or repaired. In use, it has been found to improve the effective tone of the bell by enforcing a quick, sharp blow, with no hesitation upon the surface of the bell.

It will be understood that modifications may be made in my invention without departing from the spirit thereof, and also that one or more of my devices may be used in a single bell.

Having thus described my invention, what I claim as new and desire to secure by Letters Patent, is:—

1. In a controlling device for bells, a clapper pivoted to swing and strike said bell, a member fixed relatively to the top of said bell, and tension means connecting said member and said clapper below the pivotal point of the clapper.

2. In a controlling device for bells, a clapper pivoted to swing in substantially a single plane and strike said bell, an arm fixed relatively to the top of said bell and extending within said bell in substantial parallelism with the axis thereof, and spring tension means connecting said clapper and said arm below the pivotal point of the clapper.

3. In a controlling device for bells, a clapper pivoted to swing in substantially a single plane and strike said bell, an arm fixed relatively to the top of said bell and extending within said bell in general parallelism with the axis thereof, but offset from the plane of movement of said clapper, and a coil spring connecting said arm and said clapper below the pivotal point of the clapper.

4. In a controlling device for bells, a clapper pivoted to swing in substantially a single plane and strike said bell, an arm fixed relative to the top of said bell and extending within said bell in substantial parallelism with the axis thereof, and tension means connecting the end of said arm and said clapper below the pivotal point of the clapper, said means comprising a coil spring.

5. In a controlling device for bells, a clapper pivoted to swing in substantially a single plane and strike said bell, an arm fixed relative to the top of said bell and extending within said bell in substantial parallelism with the axis thereof, and tension means con-

necting the end of said arm and said clapper below the pivotal point of the clapper, said means comprising a coil spring, said spring arranged to be free when said clapper lies along the axis of said bell, said tension increasing as said clapper moves in either direction away from said axis.

6. In combination with a bell, its clapper, and the pivotal mounting of the clapper in the upper part of the bell whereon said clapper swings to strike lower parts of the bell, a downward extension from the top of the bell, substantially fixed relatively to the bell, and a resilient connection from said extension to said clapper, below said pivotal mounting, adapted to resist the motion of the clapper as it strikes the bell.
